TOY FIGURE

Adolph E Goldfarb, 4614 Monarca Drive, Tarzana, Calif. 91345, and Erwin Benkoe, 17965 Medley Drive, Encino, Calif. 91316, and Dennis H. Merino, El Dorado Hills, Calif.; said Merino assignor to said Goldfarb and Benkoe

Filed Feb. 10, 1975, Ser. No. 548,690

Term of patent 14 years

Int. Cl. D21—01

U.S. Cl. D34—4 R

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a top view of a toy figure showing our new design;

FIG. 2 is a front view thereof;

FIG. 3 is a side view thereof;

FIG. 4 is a rear view thereof;

FIG. 5 is a top view of a modified form of head for the toy figure comprising an alternate embodiment thereof;

FIG. 6 is a front view of the head of FIG. 5;

FIG. 7 is a side view of the head of FIGS. 5 and 6;

FIG. 8 is a rear view of the head of FIGS. 5, 6 and 7;

FIG. 9 is a top view of another modified form of head for the toy figure comprising a further alternate embodiment thereof;

FIG. 10 is a front view of the head of FIG. 9;

FIG. 11 is a side view of the head of FIGS. 9 and 10; and

FIG. 12 is a rear view of the head of FIGS. 9, 10 and 11.

We claim:

The ornamental design for a toy figure, as shown and described.
